(57) **CLAIM**

The ornamental design for an electrical tester, as shown and described.

DESCRIPTION

FIG. 1 is a rear perspective view of a first construction of an electrical tester.

FIG. 2 is a front view of the electrical tester of FIG. 1.

FIG. 3 is a rear view of the electrical tester of FIG. 1.

FIG. 4 is a left side view of the electrical tester of FIG. 1.

FIG. 5 is a right side view of the electrical tester of FIG. 1.

FIG. 6 is a top view of the electrical tester of FIG. 1.

FIG. 7 is a bottom view of the electrical tester of FIG. 1.

FIG. 8 is a rear perspective view of a second construction of an electrical tester including a wire clip. Wires and an alternative, pivoted position for the wire clip are also shown in broken lines.

FIG. 9 is a front view of the electrical tester of FIG. 8.

FIG. 10 is a rear view of the electrical tester of FIG. 8.

FIG. 11 is a left side view of the electrical tester of FIG. 8.

FIG. 12 is a right side view of the electrical tester of FIG. 8.

FIG. 13 is a top view of the electrical tester of FIG. 8; and,

FIG. 14 is a bottom view of the electrical tester of FIG. 8.

The ornamental design which is claimed is shown in solid lines in the drawings. The portions of the design shown in broken lines are included for the purpose of illustrating environment and form no part of the claimed design.
